DESIGN FOR A HOBBYHORSE

John E. Hills, St. Petersburg, Fla.

Application July 1, 1936, Serial No. 63,605

Term of patent 3½ years

To all whom it may concern:

Be it known that I, John E. Hills, a citizen of the United States, residing at St. Petersburg, in the county of Pinellas and State of Florida, have invented a new, original, and ornamental Design for Hobbyhorse, of which the following is a specification, reference being had to the accompanying drawing, forming part hereof, wherein

Fig. 1 is a side elevational view of a hobby horse showing my new design; and

Fig. 2 is a front elevational view thereof.

I claim:

The ornamental design for a hobby horse, substantially as shown.

JOHN E. HILLS.
